UNITED STATES PATENT OFFICE.

CHARLES H. ALLEN, OF CHICAGO, ILLINOIS.

HEADLIGHT.

1,416,434.

Specification of Letters Patent. Patented May 16, 1922.

Application filed October 18, 1920. Serial No. 417,648.

To all whom it may concern:

Be it known that I, CHARLES H. ALLEN, a citizen of the United States, and a resident of the city of Chicago, in the county of Cook and State of Illinois, have invented certain new and useful Improvements in a Headlight; and I do hereby declare that the following is a full, clear, and exact description of the same, reference being had to the accompanying drawings, and to the numerals of reference marked thereon, which form a part of this specification.

This invention relates more particularly to a headlight for vehicles or automobiles in which reflectors are utilized to reflect the luminous rays in horizontal lines to a vertical lens and in which a separate pilot light and reflector are used to diverge the rays thereof downwardly and is an improvement 20 of my pending application Serial No. 399,736, filed July 29, 1920.

It is an object of this invention to use a system of reflectors that will project the luminous rays of light in horizontal lines 25 below a certain elevation to a plain lens.

And it is a further object of my invention to provide a separate pilot or auxiliary light and a reflector therefor which will reflect the rays downwardly through a plain lens for 30 the purpose of displaying the road and contour thereof in front of the machine.

Other and further objects will be apparent from the following description and disclosures in the drawings.

35 My invention (in a preferred form) is illustrated in the drawings and hereinafter more fully described.

In the drawings—

Figure 1 is a central vertical section 40 through my headlight.

Figure 2 is a front face view thereof on a smaller scale.

Figure 3 is a rear view of the same on a smaller scale.

45 Figure 4 is a section on the line 4—4 of Figure 1.

Figure 5 is a section on the line 5—5 of Figure 1.

As shown in the drawings—

50 Similar features are denoted by similar reference numerals in the different view.

In referring to the drawings, it will be noted that my improved headlight comprises a pair of reflectors so arranged that the 55 luminous rays of light leave the last reflector in horizontal planes, and pass unrefracted through a plain lens, and that a pilot or auxiliary light having a separate reflector is used to light the way directly in front of the moving vehicle or automobile; it is therefore possible to extinguish the main light and use merely the pilot or auxiliary light where city ordinances or regulations have placed certain restrictions on the lights used, such as the elevation or volume of the luminous rays.

60 In Figure 1, I have illustrated a headlight structure comprising a hood member 1 having a curved base terminating in a curved rear portion 2 which connects with an upwardly inclined rear portion 3 and at the top, a short curved portion 4 is formed, producing a substantially oval shaped front. The front part of the hood is closed by a metal plate 5 or the like having a main lens 6 and an auxiliary lens 7 secured in apertures 65 therein as shown in Figures 1 and 2. The exact shape and form of the hood may however be varied and changed, to suit any particular arrangement. The present device is merely 70 illustrative of a form adapted for the arrangement of reflectors used.

75 Within the hood, there is secured a substantially parabolic shaped reflector 8 of any suitable material such as a mirror for example and which is provided with boss 9 at its apex which extends through an aperture in the base and is secured by means of the nuts 10. Centrally of the boss 9 extends an incandescent lamp 11 or the like which I term the main light and which is secured in any approved manner in the boss 9 of the reflector 8. The bulb of the light 11 may be so constructed or formed that the emergence of certain objectionable rays will be obstructed so that substantially only rays which are vertically reflected from the reflector 8 will be emitted therefrom.

80 The inclined rear portion is preferably arranged at an angle of 45° with a horizontal 85 or vertical plane for supporting the reflector 12 in parallel relation therewith; for this purpose, said inclined portion may be provided with an apertured boss 13 to which the reflector is secured by means of a bolt and nut 14 or the like. The reflector 12 is of such a size and shape as to receive all the vertical rays reflected from the reflector 8, and may comprise any material having a highly polished reflecting surface.

85 In the lower front central part of the base, is secured a pilot or auxiliary light 15 sup-

ported in a block 16 having an upper face inclined at substantially an angle of 45° ; the light 15 being mounted substantially normal to said surface, so as to be inclined toward the lens 7. The block 16 and pilot light 15 are inclosed between the lens 7 and a curved reflector 17, and the curvature and arrangement is such that the luminous rays that are emitted from light 15 will be reflected in a downward direction from the reflector 17, and pass through the lens 15 where a slight refraction will occur according to the index of refraction of the glass used; the emergent rays being however parallel to the incident rays, so the downward course of the rays will continue. It is well known that the angle of reflection is equal to the angle of incidence, so the curvature of the reflector 17 can be easily designed to give the reflected rays a downward course.

In using the headlight shown, the same is supported upon its base, so that the front face will be in a vertical plane, and assuming that the lights are turned on, the emitted rays will strike the parabolic reflector 8 and the majority thereof will be reflected in vertical planes, or planes parallel to the axis of the parabolic curve, since most of the rays of light will strike the reflector at such an angle that an equal angle of the reflected ray will produce a ray in a vertical plane, for the angles of incidence and reflection are equal. Hence these vertical rays will strike the reflector 12 at an angle of 45° and the reflected rays will likewise be at an angle of 45° , which angle will produce horizontal rays passing through the lens 6. It should be understood that while I have used the terms vertical and horizontal, they are merely relative terms corresponding with the position the device is illustrated. It is therefore obvious that either of the lights may be extinguished as occasion may require, and on highways where the main glaring lights are objectionable, the pilot lights will afford ample service, and on long country roads, where it is desirable to view the road some distance ahead as well as the immediate contour in front of the automobile or vehicle, both lights can be advantageously used. In connection with the foregoing de-

scription it is to be particularly noted that the improved head-light of this invention may often be advantageously used in a reversed position from the one shown. When the headlight is used in this manner, rays from the main light which do not strike the main reflector 8 to be reflected axially therefrom, are thrown downwardly on the highway immediately in front of the vehicle and efficiently illuminate the same. In this case the pilot light is used merely as signal or dimmer light for city driving where a strong light is not necessary.

It will accordingly be observed that I have devised a headlight which possesses the advantages of meeting any need or requirement in touring either city or country roads, which utilizes to the best advantage the theory of light reflection, making it possible to direct the main luminous ray producing light in a different direction than toward the front of the car. It should be particularly noted that the light 11 is concealed from horizontal view by means of the reflector 8 and that only the emitted rays are exhibited.

I claim as my invention:

In a headlight, a casing having a lower base portion, a parabolic reflector secured in said base portion, an incandescent light secured centrally of said reflector and extending upwardly, a reflector secured to the back of said casing at an angle to the axis of the parabolic reflector, a supporting member secured on said base in front of the parabolic reflector, a pilot light secured to said supporting member and inclined forwardly with respect to the base, a lens holder in the front of said casing, an upper main lens secured in said holder, a lower pilot light lens secured in said holder, and a curved reflector extending from the top of said pilot lens to the said base and secured to the rear portion of said pilot light supporting member.

In testimony whereof I have hereunto subscribed my name in the presence of two subscribing witnesses.

CHARLES H. ALLEN.
